CONTINUOUSLY VARIABLE RESISTOR

William J. Mairs, Waltham, Mass., assignor to
Technology Instrument Corporation, Acton,
Mass.

Application October 30, 1951, Serial No. 253,815

2 Claims. (Cl. 201—59)

1

The present invention relates to a continuously variable resistor, and more particularly to a variable resistor having characteristics of the slide wire potentiometer.

The slide wire potentiometer provides a continuously variable resistor having particular utility in certain applications. A continuously variable resistor of this type is often times needed in a more compact form, and hence there have been provided helically wound resistors having a contact which moves in a helical path to engage the resistance wire. Such arrangements, however, involve certain complex constructions in order to move the contact along the resistance wire without introducing an additional resistance factor due to improper contact with the wire. Such arrangements furthermore are limited to a linear relation between the movement of the actuating control and the resistance element.

In accordance with the present invention it is proposed to obviate certain disadvantages heretofore encountered in the construction of a compact continuously variable resistor of the potentiometer type by holding the contact stationary and moving the resistance wire or flexible resistance element thereacross. Furthermore, an arrangement can be provided for a non-linear change of the contact with respect to the resistance wire for a uniform movement of the actuating control.

Therefore, it is an object of the present invention to provide a new and improved compact continuously variable resistor of the potentiometer type.

Another object of the invention is to provide an improved compact continuously variable resistor wherein the adjustable wire contact is held stationary.

Other and further objects of the present invention subsequently will become apparent by reference to the present description taken in conjunction with the accompanying drawing wherein:

Figure 1 is a top view of a continuously variable resistor embodying the principles of the present invention;

Figure 2 is a rear view of the device shown in Figure 1;

Figure 3 is a cross sectional view of one portion of the device shown in Figure 1; and

Figure 4 is a top view of a device similar to Figure 1 wherein a non-linear relationship is obtained.

Referring to Figures 1 and 2 of the drawing there will be seen a supporting panel 11 which carries a control shaft 12 passing through a suit-

2

able bushing and having a locking collar 13 at its end. The control shaft 12 carries a gear 14 at the front of the supporting panel 11 which is engaged by two other gears 15 and 16 mounted on shafts 17 and 18. The shaft 17 carries a groove insulated reel 19 and a similar grooved reel 21 is mounted on the shaft 18. A flexible resistance element or wire 22 is wound in the grooves of the two insulated reels 19 and 21. The resistance element or wire 22 is wound on to one of the reels and off from the other reel. The resistance element or wire 22 in moving from one reel to another engages an electric contact strip carried by a support rod 23.

The shafts 17 and 18 are mounted in suitable bushings carried by the panel 11 and held in position by lock nuts 25 and 26 respectively.

In order that the resistance element or wire 22 will be in proper contact with the stationary contact strip 24, the insulated reel 19 may have construction such as that illustrated in detail in Figure 3. It will be noted that the reel 19 has an internal bore 28 which engages a sleeve 29. The reel will be retained or locked in position on the sleeve 29 by a set screw 31 which also serves as an electric terminal for one end of the resistance element or wire 22. The other end of the resistance element or wire 22 may be connected directly to the shaft 18.

A helical spring 34 interconnects the sleeve 29 with a collar 32 affixed to the end of the shaft 19 by a suitable clamping screw 33 as may be seen for figure 32. The spring 33 is so arranged as to provide a biasing force between the shaft 17 and the reel 19 so that the resistance element or wire 22 is always subjected to a certain degree of tension. There is an arrangement provided for maintaining good electric contact between the stationary contact 24 and the resistance element or wire 22 irrespective to slight irregularities in manufacture of the two insulated reels 19 and 21 or any lost motion and backlash between the gears 14, 15 and 16.

In the event that a non-linear relationship is desired between the movement of the control shaft and the movement of the wire across the stationary contact an arrangement similar to that shown in Figure 4 may be employed. A panel 35 carries on suitable shafts frusto-conical reels 36 and 37 on which grooves are provided for a flexible resistance element or wire which engages the stationary contact carried between support rod 38. It is believed that it now will be apparent to those skilled in the art that other configurations may be provided for the rotatable insula-

tor members 36 and 37 so that a desired non-linear relation can be obtained.

While for the purpose of illustrating and describing the invention a preferred embodiment has been shown in the drawing, it is to be understood that the invention is not to be limited thereby, since such variations are contemplated, as may be commensurate with the purpose and scope of the invention set forth in the accompanying claims.

I claim as my invention:

1. A continuously variable resistor comprising a vertical support panel, two shafts mounted perpendicular to one side of said panel, two insulated grooved non-cylindrical drums mounted on said shafts, one of said drums being fixed to its shaft, the other drum being mounted for rotation relative to its shaft, means for simultaneously rotating said shafts, a resistance wire mounted in the grooves of said drums to be unwound on to the other, a sliding stationary contact mounted between said drums parallel to the surfaces thereof and beyond a plane tangent to the surfaces of said drums, means for maintaining substantially constant contact between said sliding stationary contact and said wire comprising a helical spring interposed between the shaft and said latter drum tending to produce rotation of said drum relative to its support shaft.

2. A continuously variable resistor comprising

5 a vertical support panel having mounted thereon two parallel rotatable shafts, two insulated grooved frusto-conical drums mounted on said shafts, one of said drums being fixed to its shaft, the other drum being mounted for limited rotation relative to its shaft, means for simultaneously rotating said shafts, a resistance wire mounted in the grooves of said drums to be unwound from one drum and wound on to the other drum, a sliding stationary contact mounted between said drums generally parallel to the longitudinal surfaces thereof and beyond a plane tangent to the surfaces of said drums, means for maintaining substantially constant the contact between said sliding stationary contact and said wire comprising a spring interposed between the shaft and said latter drum tending to produce rotation thereof relative to said shaft, and means for continuously making electrical contact with the ends of said wire.

10 15 20 25 WILLIAM J. MAIRS.
